CLAIM

We claim the ornamental design for a firearm handguard, as shown and described.

DESCRIPTION

FIG. 1 is a perspective view of a first embodiment of a firearm handguard;

FIG. 2 is a first end view of the first embodiment;

FIG. 3 is a first side view of the first embodiment;

FIG. 4 is second end view of the first embodiment;

FIG. 5 is a top view of the first embodiment;

FIG. 6 is a second side view of the first embodiment;

FIG. 7 is a bottom view of the first embodiment;

FIG. 8 is a perspective view of a second embodiment of a firearm handguard;

FIG. 9 is a first end view of the second embodiment;

FIG. 10 is a first side view of the second embodiment;

FIG. 11 is second end view of the second embodiment;

FIG. 12 is a top view of the second embodiment;

FIG. 13 is a second side view of the second embodiment; and,

FIG. 14 is a bottom view of the second embodiment.

The portions of the firearm handguard shown in broken lines form no part of the claimed design.
